UNITED STATES PATENT OFFICE

104,724

DESIGN FOR A LOLLIPOP FIGURE

Harry J. Lasher, Bennington, Vt., assignor to Bennington Wax Paper Company, Bennington, Vt.

Application April 2, 1937, Serial No. 68,537

Term of patent 7 years

To all whom it may concern:

Be it known that I, Harry J. Lasher, a citizen of the United States, residing at Bennington, in the county of Bennington and State of Vermont, have invented a new, original, and ornamental Design for a Lollipop Figure, of which the following is a specification, reference being had to the accompanying drawing, forming part hereof:—

I claim:

The ornamental design for a lollipop figure, as shown.

HARRY J. LASHER.
